(57) **CLAIM**

The ornamental design for a transparent case for an electronic communication device, as shown and described.

DESCRIPTION

FIG. 1 is a rear isometric view of a transparent case for an electronic communication device.

FIG. 2 is a front isometric view of the transparent case for an electronic communication device of FIG. 1.

FIG. 3 is a rear view of the transparent case for an electronic communication device of FIG. 1.

FIG. 4 is a front view of the transparent case for an electronic communication device of FIG. 1.

FIG. 5 is a right side view of the transparent case for an electronic communication device of FIG. 1.

FIG. 6 is a left side view of the transparent case for an electronic communication device of FIG. 1.

FIG. 7 is a top view of the transparent case for an electronic communication device of FIG. 1; and,

FIG. 8 is a bottom view of the transparent case for an electronic communication device of FIG. 1.

The broken line in the drawings depicts unclaimed portion of the case only and forms no part of the claimed design.

1 Claim, 8 Drawing Sheets
